FIG. 1 is a top plan view of a tray for unitary dosage system showing our new design;

FIG. 2 is a bottom plan view thereof;

FIG. 3 is a side elevational view thereof;

FIG. 4 is a section therethrough taken at line 4-4 in FIG. 1 and viewed in the direction of the arrows;

FIG. 5 is an end elevational view on a somewhat larger scale than the other figures;

FIG. 6 is a section taken at line 6-6 in FIG. 1 and viewed in the direction of the arrows and presented on the same scale as FIG. 5;

FIG. 7 is a perspective view as seen from the front and top of the tray illustrated in FIGS. 1 through 6;

FIG. 8 is a perspective view as seen from the rear and bottom of the tray illustrated in FIGS. 1 through 6, with the longitudinally extending ribs removed therefrom; and

FIG. 9 is a perspective view of the tray illustrated in FIGS. 1 through 6 as seen from the rear and bottom, similar in all respects to the view of FIG. 8 except that the ribs removed in FIG. 8 are shown in full.

We claim:

The ornamental design for a tray for unitary dosage system, as shown and described.
